[57] CLAIM

The ornamental design for a battery pack with removable clip, as shown and described.

DESCRIPTION

FIG. 1 is a top perspective view of the battery pack with removable clip showing my new design;

FIG. 2 is a front elevational view thereof;

FIG. 3 is a right side elevational view;

FIG. 4 is a left side elevational view;

FIG. 5 is a top plan view thereof;

FIG. 6 is a bottom plan view thereof;

FIG. 7 is a back elevational view; and

FIG. 8 is a top perspective view thereof with the removable clip shown positioned on the top surface thereof.

FIG. 1

FIG. 3

FIG. 4

FIG. 5

FIG. 2

FIG. 6

FIG. 7

FIG. 8
